(57) **CLAIM**

The ornamental design for a casino game table, as shown and described.

DESCRIPTION

FIG. 1 is a plan view of the casino game table design of the claimed invention showing a plurality of identical player game stations.

FIG. 2 is an enlarged view of one of the player game stations shown in FIG. 1.

FIG. 3 is an enlarged view of the dice throw box shown in FIG. 1, shown broken away for ease of illustration.

FIG. 4 is a perspective view of the dice throw box shown in FIG. 3.

FIG. 5 is a bottom view thereof;

FIG. 6 is a front view thereof;

FIG. 7 is a rear view thereof;

FIG. 8 is a right side view thereof; and,

FIG. 9 is a left side view thereof.

The broken line showing of the indicia is environmental material, and is not considered part of the claimed design.
